UNITED STATES PATENT OFFICE.

CARY HOLLIS NELSON, OF DENVER, COLORADO.

MOLD.

Application filed February 24, 1925. Serial No. 11,135.

To all whom it may concern:

Be it known that I, CARY HOLLIS NELSON, citizen of the United States, residing at Denver, in the city and county of Denver and State of Colorado, have invented certain new and useful Improvements in Molds; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to improvements in the design and construction of molds for constructing walls for concrete or gypsum.

As our country increases in population and our supply of timber decreases, it becomes 20 more and more evident that resort must be had to cement and gypsum as the material for building construction. I am, of course, aware that both cement and gypsum have been employed in the construction of buildings and that various types of forms or molds have been employed for this purpose, all of which, however, are difficult to assemble and slow in operation.

It is the object of this invention to produce a mold that can be conveniently placed 30 in position and readily moved and which is also adapted to be moved upwardly continuously at a slow rate, which makes it very well adapted for use with gypsum which sets 35 quicker than cement.

It is a further object of this invention to produce molds that are adapted to be arranged in series or at an angle to each other so that they may be used for building all 40 the outside and partition walls practically simultaneously.

The above and other objects that will become apparent as the description proceeds are attained by means of a construction that 45 I will now describe in detail, reference for this purpose being had to the accompanying drawing in which one embodiment of my invention is shown and in which

Fig. 1 is a perspective view showing a 50 section of wall with my mold in place thereon.

Fig. 2 is a detail showing the manner in which the bars forming the apron are hinged.

Fig. 3 is a section taken on line 3—3 Fig. 2. 55 Fig. 4 is a vertical transverse section taken on line 4—4, Fig. 5.

Fig. 5 is a section taken on line 5—5, Fig. 4, and

Fig. 6 is a view looking down onto a corner of a building and shows a part of 60 two forms in place.

Numeral 1 in Fig. 1 indicates a concrete wall to which my improved form is applied. The form comprises two yokes, each consisting of two L-shaped members 2 and 3, 65 which are secured together by means of bolts 4. The member 2 has spaced flanges 5 between which the end 6 of member 3 fits. By changing the position of the bolts 4 the distance between the vertical portions of members 2 and 3 may be adjusted. Rollers 7 and 8 are rotatably mounted at 9 and 10 respectively. An endless apron 11 is applied to the rollers 7 and 8 in the manner analogous 70 to a belt. These aprons are formed by a 75 number of flat bars 12 such, for example, as two by four scantlings. These bars are connected by hinges, in the manner shown in Figs. 2 and 3. These hinges have been shown as formed from links 13 whose ends 80 are joined by pins 14, so as to form an endless chain. The bars 13 are secured to the links by means of screws 15. The bars 12, when applied to the rollers, form what might 85 be termed caterpillar treads. These treads are parallel and their adjacent surfaces form the sides of the mold in the manner clearly apparent from Fig. 1. It is evident that when concrete or gypsum in flowing condition is put into place between the sides of 90 the form that a considerable pressure is exerted on the sides which will cause them to bend unless means is provided that will prevent them from so doing. I have therefore joined the vertical parallel sides of 95 members 2 and 3 by several parallel bars 16 whose ends are secured to the inside of the bars by brackets 17, or other equivalent means. Vertical bars 18 are supported on the horizontal bars 17. These vertical bars 100 form rigid supports that prevent the sides of the mold from bending.

In Fig. 6 I have shown a corner of a building and have indicated how my mold is applied. A large angle 19 forms the outside and a smaller but similar angle 20, the inside. These two angles form the sides of the mold for the corner, and may be held in assembled relation by means of bolts 21. Secured to the inner surfaces of the flanges 22 and 23 of the angle iron 20 are Z-bars 24 that form guides for the vertical sides of 105 110

members 2 and 3. Similar guides are provided at the other end of the forms. These forms may either be moved upwardly from time to time as occasion requires or they 5 may be moved continuously at a slow even rate of speed as is desirable when the building material employed is gypsum as this sets in a much shorter time than concrete. As it is possible to employ several specifically different means for hoisting the forms, I have not attempted to illustrate any one form but have merely shown chains 24 that may be attached to any suitable hoisting mechanism. I have shown only a single section of 10 my form and indicated how it may be employed to build a square corner as the details concerning the actual manner of using the form has nothing to do with the invention which is considered to be in the construction of the form itself. It is, however, possible to arrange my forms so that the walls and partitions of an entire house may be built at one time. Walls of any length and of any thickness may also be built by 15 using several sections in series or by changing the adjustment between the members 2 and 3.

From the above it will be apparent that I have produced a form of novel construction 20 that can be readily moved as the condition of the work requires.

Having described my invention, what I claim as new is:

1. A mold for building walls from plastic 25 material, comprising, in combination, two U-shaped frames having corresponding sides connected by two parallel spaced rollers, an

endless flexible belt enclosing each pair of said rollers, the adjacent sides of said belt being spaced to form the sides of the mold. 40

2. A mold for use in building walls from plastic material, comprising, in combination, two U-shaped frame members located in spaced parallel planes, each side of said members being connected to the corresponding side of the other member by shafts carrying rollers, an endless belt enclosing the rollers connected to each pair of sides, said belts having their adjacent surfaces parallel and spaced apart. 45

3. A mold for use in building walls from plastic material, comprising, in combination, two U-shaped frame members located in spaced parallel planes, means for adjusting the distance between the sides of said frames, rollers connecting corresponding sides of the frames, and an endless belt being formed from straight bars hingedly connected so as to be bendable in one direction but not 50 the other direction. 55

4. A mold for use in building walls from plastic material, comprising, in combination, two U-shaped frame members located in spaced parallel planes, means for adjusting the distance between the sides of said frames, a pair of rollers connecting corresponding sides of the frames, an endless belt enclosing each pair of rollers and rigid members secured to the said frames between the sides of the belt, said rigid members serving as a 60 backing for preventing the belts from bending. 65

In testimony whereof I affix my signature.
CARY HOLLIS NELSON. 70
